US0D1002577S

(12) **United States Design Patent** (10) **Patent No.:** **US D1,002,577 S**
(45) **Date of Patent:** **** Oct. 24, 2023**

(54) **SPEAKER**

(71) Applicant: **Amazon Technologies, Inc.**, Seattle, WA (US)

(72) Inventors: **Michael Edward James Paterson**, Lafayette, CA (US); **Giles David Matthew McWilliam**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/803,102**

(22) Filed: **Aug. 10, 2021**

Related U.S. Application Data

(62) Division of application No. 29/650,422, filed on Jun. 6, 2018, now Pat. No. Des. 929,367.

CLAIM

The ornamental design for a speaker, as shown and described.

DESCRIPTION

FIG. 1 is a top perspective view of a speaker; FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the speaker that form no part of the claimed design. The dot-dashed broken lines represent boundaries of the claimed speaker and form no part of the claimed design.

1 Claim, 8 Drawing Sheets
